UNITED STATES PATENT OFFICE.

ROBERT R. WHITING, OF DARIEN, CONNECTICUT.

MOORING LINE.

Application filed April 12, 1924. Serial No. 706,149.

To all whom it may concern:

Be it known that I, ROBERT R. WHITING, a citizen of the United States, and a resident of Darien, in the county of Fairfield and State of Connecticut, have invented a new and Improved Mooring Line, of which the following is a full, clear, and exact description.

The present invention relates to new and useful improvements in strain-relieving devices, and it pertains more particularly to a device of this character especially adapted for attachment to mooring lines of vessels.

It is one of the primary objects of the invention to provide a strain-taking device adapted to be interposed between the ends of a mooring line for the purpose of relieving the line of strain occasioned by the movement of a vessel relative to its mooring.

It is a further object of the invention to provide a device of this character which may be attached to mooring lines of any size, it being detachable with respect to the line.

With the above and other objects in view, reference is had to the accompanying drawings, in which—

Figure 1 is a view in elevation of a mooring line showing the device attached thereto;

Fig. 2 is a detail view of the device detached from the line;

Fig. 3 is a sectional view taken on the line 3—3 of Fig. 1;

Fig. 4 is a detail plan view of a slightly modified form of the invention;

Fig. 5 is a detail sectional view taken on the line 5—5 of Fig. 4.

Referring more specifically to the drawings, the reference character A designates the mooring line, the strain-relieving device comprising two clamps 5 adapted to be secured, by means of bolts 6 or the like, around the mooring line A. The clamp members 5 comprise a split band as more clearly shown

in Fig. 3. These clamps are connected together by means of a spring element 8. This 45 spring element may be secured to the clamps 5 in any desired manner, such, for example, as by bolts 9 or the like, or, as shown in Fig. 4, the spring may be a coil spring secured by bolts designated by the 50 reference numeral 10.

In securing the device in place, a bight B is made in the mooring line and the clamps 5 are engaged with the mooring line on opposite sides of such bight B. If, now, the 55 mooring line A is subjected to strain, the spring or resilient member interposed between the clamps will take the strain, the bight B of the mooring line A allowing sufficient play in the mooring line to permit 60 of this action.

By providing a device of this character between the ends of a mooring line, it is obvious that as the ship pitches or rolls at its mooring, the strain on the mooring line A 65 will be relieved and transferred to the resilient member of the strain-relieving device and prevent a rupture of the mooring line.

What is claimed is:

1. A strain-relieving device in lines, comprising in combination with a mooring line, a plurality of clamps adapted to be secured to the mooring line, a bight formed in the mooring line between said clamps, and means connecting said clamps, said means 70 consisting of a resilient element.

2. A strain-relieving device for lines, comprising in combination with a mooring line, a plurality of clamps adapted to be secured to the mooring line, a bight formed in the 80 mooring line between said clamps, and means connecting said clamps, said means comprising a resilient element removably secured to the clamps.

ROBERT R. WHITING.
